DESIGN.

A. ROSENSTEIN.

CANE OR UMBRELLA HANDLE.

D
No. 20,164.

Patented Sept. 23, 1890.

UNITED STATES PATENT OFFICE.

ALBERT ROSENSTEIN, OF LANCASTER, PENNSYLVANIA.

DESIGN FOR A CANE OR UMBRELLA HANDLE.

SPECIFICATION forming part of Design No. 20,164, dated September 23, 1890.

Application filed August 1, 1890. Serial No. 360,670. Term of patent 3½ years.

To all whom it may concern:

Be it known that I, ALBERT ROSENSTEIN, of Lancaster, in the county of Lancaster and State of Pennsylvania, have invented certain 5 new and useful Improvements in Designs for Cane, Umbrella, or Parasol Handles; and I do hereby declare the following to be a full, clear, and exact description of the invention, such as will enable others skilled in the art to 10 to which it pertains to make and use it, reference being had to the accompanying drawing, which forms part of this specification.

My invention relates to an improvement in 15 designs for cane, umbrella, or parasol handles; and it consists in the novel shape and configuration of parts, whereby a pleasing and beautiful effect is produced, as will be more fully described hereinafter.

The accompanying photographic illustration 20 represents my invention.

A represents the inner end of the handle, which has the two beads B extending horizontally around it at any desired distance apart. The outer end of the handle is given the appearance of a streamer C, which is folded or 25 doubled around a tapering body D so as to

form a support therefor, and which streamer has its end wrapped around so as to rest against and form a part of the main portion of the handle. The body D apparently passes 30 through the opening G made in the double part of the streamer and extends at any suitable angle to that part of the handle that is formed by the streamer. The body D is made tapering, as here shown, and has the representation of a ball or rounded object I secured to its smaller end. 35

The design as here shown produces a neat and tasteful appearance and adds greatly to the beauty of the cane, umbrella, or parasol 40 to which it is secured.

Having thus described my invention, I claim—

The design for a cane, parasol, or umbrella handle, substantially as herein shown and described. 45

In testimony whereof I affix my signature in presence of two witnesses.

ALBERT ROSENSTEIN.

Witnesses:

E. P. ELLIS,

ALLEN S. PATTISON.
